UNITED STATES PATENT OFFICE.

EUGENE F. AHLQUIST, OF MINNEAPOLIS, MINNESOTA, ASSIGNOR TO GAW-O'HARA ENVELOPE COMPANY, OF CHICAGO, ILLINOIS, A CORPORATION OF ILLINOIS.

ENVELOPE.

Application filed March 18, 1928. Serial No. 95,524.

My invention relates to envelopes, and particularly to envelopes for mailing purposes which the Post Office regulations require to be sealed with wax in order to prevent tampering with the same during their transmission.

Envelopes of the type contemplated by my invention are used for mailing securities, currency, and the like. Before the Post Office will register and insure the same, it is required that all the parts comprising the envelope be sealed together by wax, and in the common form of envelope used at the present time, three seals are required to secure all the adjoining and abutting edges. Considerable time is consumed in placing the sealing wax upon these different points of contact on the present form of envelope, and the weight of the seals constitutes quite a factor in the mailing expense.

The object of my invention is to provide a cheap and simple form of mailing envelope wherein all the overlapping, abutting edges are concentrated at one point and at this point a single application of sealing wax will seal all the parts together, so that they cannot be disconnected without fracturing or otherwise distorting the sealing wax, so that any tampering with the envelope will be apparent from the condition of the wax thereon.

To these ends, my invention therefore consists of the novel manner of overlapping and joining the side wings, the bottom member, and the top flap, so that at least a portion of the same is exposed at one central point on the rear of the envelope and when sealing wax is applied to this particular point, it will be impossible to remove the contents of the envelope by steaming and withdrawing any of the parts comprising the back of the envelope without fracturing the seal or tearing the part of the envelope withdrawn. In such case, the tampering will be apparent, as the envelope and seal cannot be glued to its original condition, as would be the case with an envelope of the present day construction, where one seal was used. It will therefore be apparent that by the use

of this envelope, the time spent in placing three seals of wax upon the envelope will be greatly diminished, the cost of sealing wax, necessary for sealing each envelope, will be considerably diminished, and the weight of the envelope will be decreased, so that the cost of its transmittal through the mails will be less than with an envelope having three or more seals upon the same, all of which saving has met with great favor in the trade and has proven the invention to be a great commercial success.

The advantages and objects which have been set forth above will be more apparent when reference is had to the following description and claims when considered in connection with the accompanying drawing, in which:

Fig. 1 is a plan view of the blank from which my improved envelope is formed.

Fig. 2 shows the first step in forming the envelope by folding the side wings so as to overlap the same.

Fig. 3 is a like view showing the bottom member and a portion of the body bent upwardly to form the pocket of the envelope.

Fig. 4 is a like view showing the envelope with its sealing flap bent downward to closed position and with a single application of sealing wax for securing the parts together, and

Fig. 5 is a vertical sectional view of the closed envelope with its application of sealing wax taken on the line 5—5 of Fig. 4.

Like symbols of reference herein indicate like parts in each of the figures of the drawing.

As indicated in the drawing, and particularly in Fig. 1, my improved envelope is formed from a single blank of any desired material, such as paper, fibroid, flexible fiber paper etc., and these blanks are cut to the shape shown with a suitable die. The blank has a central body portion 6 and side wings 7 and 8 on the respective sides thereof, a bottom member 9 with a recess 11 therein, and a top or closing flap 12. In the first operation of forming the envelope, the side wing 7 is bent over onto the body portion 6

on the line 13, and the side wing 8 is bent over onto the said body portion on the line 14, and the outer end of the side wing 8 falls beyond the outer edge of the side wing

5 7, so as to form the overlapping joint 16, and this overlapping joint is provided with adhesive material 17 for securing side wings 7 and 8 together. This operation is called tubing.

10 In order to form the bottom of the pocket of the envelope and to make the corners thereof secure, so that nothing can be removed from the envelope, the bottom member 9, together with a portion of the body 6

15 and portions of the side wings 7 and 8, all of which are included and characterized by the numeral 19, are bent upward on the line 21 over the remaining portions of the side wing 7 and 8, and the adhesive material 22

20 on the said bottom member, and a portion of the side wings 7 and 8 is dampened, so that said parts are secured to the remaining portions of the side wings, as shown in Fig. 3.

It will thus be seen that after the envelope 25 has been so far constructed, all the ends have been brought to a central position within and around the recess 11 in the bottom member 9, and when valuables, in the form of stock, bonds, currency, or like matter, is

30 placed in the pocket of the envelope, the closing flap 12, together with the upper portions of the side wings 7 and 8, is bent on the folded line 23 onto the remaining portion of said side wings, and moisture is applied to the adhesive material 24, so as to secure the said portions in position, and when so secured, the upper edge 26 of the closing flap will fall across the overlapping portions 16, so as to include both the side wings 7 and 8,

35 40 and will fall across the recess 11 of the bottom flap 9 so that when a single application of sealing wax 27 is applied at this point, the two side wings 7 and 8, the bottom member 9, and the closing flap 12, will be connected to the said applied sealing member 27, and thus the envelope will be insured against opening, without breaking or distorting the said sealing wax.

It will be readily observed that while I 50 have shown and described the recess 11 as being in the bottom flap 9 it may to all intents and purposes be in the closing flap 12 where it will give exactly the same results. For instance, if the flaps in the drawing 55 were reversed and the closing flap called the bottom flap and secured in the same manner and the bottom flap called the closing flap, the result obtained will be exactly the same. Hence, I do not limit myself to any exact 60 construction so long as the two side wings, bottom flap and closing flap are susceptible of having one application of sealing wax placed thereon for securing all parts together. Thus, while I have shown the recess as 65 extending inward from the edge of the flap

it will readily be seen that an opening in the body of the flap so as to include therein the edges of the two side wings and the other flap will be equally effective.

Various modifications and changes in this 70 invention will undoubtedly suggest themselves to anyone skilled in the art, and consequently I do not limit myself to the exact shape of the blank and its component parts as shown and described in the foregoing 75 specification, but embody in my invention all such variations and modifications which properly fall within the language and spirit of the appended claims.

I claim:

1. An envelope comprising a body portion, imperforate side wing portions folded over said body portion, the outer ends of the wing portions extending substantially together, and bottom and top flap portions folded over said body portion, said wing portions and one over the other, one of said flap portions having a recessed margin exposing the margin of the other flap and a portion of the surface of each of said wing portions adjacent 90 margins thereof, whereby a single wax seal may secure the wing and flap portions together.

2. An envelope comprising a body portion, imperforate side wing portions folded inwardly over said body portion with their outer free ends adjacent and overlapping one another, and bottom and top flap portions folded over said wing portions and one over the other, one of said flap portions having an opening exposing part of the surface adjacent the marginal edge of each wing portion and the other flap portion when said portions are folded into position.

3. An envelope having a central body portion, side wings folded over said body portion and having their ends overlapping and secured together, a bottom flap folded upward over said side wings and having its outer marginal edge secured thereto, a closing flap extending downward over said side wings and being adapted to be secured thereto, and portions of each of said wings, said bottom flap, and said closing flap being exposed at substantially a single common place 110 so that a single application of sealing wax 115 will contact with and secure all of said members together.

4. An envelope comprising a central body portion, side wings adapted to be folded over said body portion and having their outer edges overlapping and secured together, a bottom flap adapted to be bent upward together with a portion of said central body and portions of said side wings, a closing flap 125 adapted to be bent downward together with a portion of said central body and portions of said side wings, one of said flaps having a recess at which place portions of the edges of all of said members are exposed when 130

folded so that a single application of sealing wax will contact with and secure all of the same together.

5. An envelope having a body portion, side wings, a bottom flap, and a closing flap, one of said flaps having an aperture, said parts being so folded that a portion adjacent the edge of each of said wings and one

of said flaps meet at substantially a common point within said aperture whereby a single ¹⁰ application of sealing wax will contact with and secure said parts including said apertured flap together.

In witness of the foregoing I affix my signature.

EUGENE F. AHLQUIST.
